UNITED STATES PATENT OFFICE

JOHN A. PILCHER AND JOHN A. DOARNBERGER, OF ROANOKE, VIRGINIA

STEAM BOILER

Application filed April 24, 1925. Serial No. 25,514.

This invention pertains to steam boilers and has among its objects, to provide improved means for the securing and bracing of certain of the boiler sheets relative to each other.

In steam boilers, as in all pressure containers, it is necessary that means be provided for the bracing of flat surfaces, so that the forces acting on these flat surfaces may be transferred to some other part of the boiler, which is stronger and more suitable for absorbing them. In steam boilers of the locomotive type, the principal sheets for which this bracing must be provided, are the front and the back flue sheet and the crown sheet.

In a boiler of the locomotive type, the main bracing of the flue sheets are the flues which are secured to and extend from the front to the back flue sheet, thus displacement of the two sheets due to internal pressure is limited. However, on account of the firebox, which is located at one end, it is necessary in the construction of a locomotive type boiler that the front flue sheet be larger than the back flue sheet. This produces a larger load on the front flue sheet than on the back, and whereas the flues may be approximately uniformly distributed over the back flue sheet, they can not be so distributed over the front flue sheet. Therefore, in addition to the flues, braces are provided which transfer a part of the load on the front flue sheet to the barrel of the boiler. Even with this additional bracing on the front flue sheet, which can seldom be uniformly distributed, it has been found difficult in practice to prevent movement of the front flue sheet with respect to the barrel of the boiler. Any movement of the front flue sheet causes the back flue sheet to move also, as the two sheets are secured to each other by means of the flues. Any movement of the back flue sheet caused by forces transmitted to it through the flues and by internal pressure, will produce high stresses at certain parts of its outer edge where it is secured to other sheets of the boiler. If these stresses are set up and relieved a sufficient number of times, they will

finally result in the cracking of the flue sheet and thereby cause its renewal or repair.

Another part of a locomotive boiler where it has been found by experiment that high stresses are set up, is in the top of the crown sheet near where it is joined to the back flue sheet. The outside wrapper or barrel sheet over the front end of the crown sheet usually has a smaller radius of curvature than that portion of the crown sheet under it, and while the two are secured to each other, there is on account of unbalanced forces, a movement of the crown sheet relative to the wrapper or barrel sheet. This movement, which has been recorded in experiments, is small, but if repeated a sufficient number of times will eventually cause the failure of the top of the crown sheet near where it is secured to the back flue sheet.

The object of this invention is to provide suitable means whereby high stresses are eliminated at or near the line of junction of two or more sheets of the boiler.

With the foregoing object in view, the invention consists of the formation, combination and arrangement of parts as set forth, particularly in the appended claims, the various elements being co-ordinated to produce improvements generally in this art.

In the drawings, Fig. 1 is a fragmentary longitudinal sectional view of a boiler of the locomotive type.

Fig. 2, is a sectional view taken approximately on line 2—2 of Fig. 1, showing how the flues and braces are located on the front flue sheet.

Fig. 3 is a fragmentary sectional view taken approximately on line 3—3 of Fig. 1.

Fig. 4 is an enlarged view showing how our brace is applied to the junction of the crown sheet and the back flue sheet.

Fig. 5 is a view showing how our brace may be applied when the back flue sheet is butt-welded to the crown sheet.

Fig. 6 is a view taken approximately on line 6—6 of Fig. 5.

Fig. 7 is an enlarged fragmentary sectional view of a boiler showing the method of applying our brace to the junction of the crown and back flue sheet, when the back

flue sheet is butt-welded to the crown sheet and the crown sheet extended beyond the junction line of the two sheets.

Fig. 8 is a fragmentary sectional view of a boiler showing how the junction of the crown sheet and back flue sheet may be reinforced by crimping the crown sheet and the flue sheet.

Fig. 9 is an enlarged view taken on line 9—9 of Fig. 8.

Fig. 10 is an enlarged view taken on line 10—10 of Fig. 8.

Referring to these drawings which show one embodiment of our invention, the front flue sheet 1 is attached to the barrel 2 by means of the rivets 3. The back flue sheet 4 is welded to the combustion chamber 5, the top of which is known as the crown sheet 6, at 7. The flues 8 are secured to and extend from the front flue sheet to the back flue sheet. It will be noted that while the flues 8 may be evenly distributed over the back flue sheet, there is a portion of the front flue sheet which is not provided with flues, and while this portion is braced by means of the braces 9 which extend to the barrel of the boiler, it is very difficult to prevent movement of the front flue sheet with respect to the barrel sheet.

It will be readily seen that movement of the front flue sheet will cause the back flue sheet to move also, as the two sheets are tied together by means of the flues 8. This movement if repeated a sufficient number of times, will cause the back flue sheet to crack in the flange knuckle at a location between the top row of flues and where it is joined to the crown sheet as shown approximately at 10.

In order to reinforce the back flue sheet where this failure would occur, we have provided the brace 11, which is secured to the crown sheet 6 and the back flue sheet 4, by means of the welding 12. These braces 11 may be applied along the top of the crown sheet for a distance sufficient to prevent the failing of the crown and the back flue sheet. These braces 11 not only eliminate high fiber stress in the back flue sheet at or near the line of junction of the flue sheet and the crown sheet, but will also eliminate high fiber stress in the crown sheet at or near the line of junction of the two sheets. The braces 11 may be applied all the way around the back flue sheet if found necessary, although the failure of the flue sheet usually occurs at the top and bottom rather than at the sides.

Figures 4 and 5 are enlarged views showing how our brace 11 may be applied when the back flue sheet is flanged and welded, or when it is butt-welded to the crown sheet. Brace 11 may be readily attached to the crown sheet and back flue sheet by welding as shown at 12 in Fig. 6. It will be noted that the braces 11 are carried back on the crown sheet close to the stay-bolts 13 and

are carried down on the flue sheet close to the top of the flues 8. It will also be noted in Fig. 6, that the brace 11 may be of a bulb section in order to provide stiffness.

At Fig. 7, the crown sheet extends past the back flue sheet and a row of stay-bolts is provided in this extension. In this design, the brace 11 is a flat triangular plate welded to the flue sheet and to the extension of the crown sheet. This extension of the crown sheet beyond the line of junction of the two sheets with an additional row of stay-bolts and with the brace 11, will make the junction of the two sheets very strong and remove the possibility of failure of either sheet near their junction.

In Fig. 8, the crown sheet 6 and the flue sheet 4 are crimped near where they are joined together as shown at 14. The crown sheet and flue sheet are cut to fit this crimping and the two are welded together as shown at 7 in Figs. 9 and 10. With this method of securing the two sheets to each other, the brace may be omitted, as the crimping will provide sufficient stiffness and transfer the high stresses away from the junction of the two sheets.

Having described our invention, what we claim is:

1. In a steam boiler, the combination of a flue sheet and a crown sheet, means rigidly securing said sheets to each other; said means including bracing means disposed at intervals on the water side of said sheets and in planes substantially at right angles to the planes of the said sheets, said bracing means bridging the junction line and acting to insure against relative movement of the adjoining portions of the said sheets.

2. In a locomotive steam boiler, the combination of a back flue sheet and fire box sheets rigidly secured thereto, said fire box sheets being disposed in planes substantially at right angles to said back flue sheet, bracing means disposed at intervals on the water side of said sheets in planes substantially at right angles thereto, said bracing means bridging the junction line of said sheets to insure against relative movement of the adjoining portions of said sheets.

JOHN A. PILCHER.
